UNITED STATES PATENT OFFICE

170,259

BABY JUMPER

Bertis F. Hamilton, Columbus, Ind.

Application April 1, 1953, Serial No. 24,297

Term of patent 14 years

(Cl. D15—1)

To all whom it may concern:

Be it known that I, Bertis F. Hamilton, a citizen of the United States, residing at Columbus, county of Bartholomew, State of Indiana, have invented a new, original, and ornamental Design for a Baby Jumper, of which the following is a specification, reference being had to the accompanying drawings, forming a part hereof.

Fig. 1 is a front perspective view of a baby jumper, showing my new design; and

Fig. 2 is a rear perspective view thereof.

I claim:

The ornamental design for a baby jumper, as shown.

BERTIS F. HAMILTON.
